US00D719857S

(12) **United States Design Patent**
Groener et al.

(10) **Patent No.:** **US D719,857 S**
(45) **Date of Patent:** **** Dec. 23, 2014**

(54) **ELECTRONIC DEVICE**

(71) **Applicant:** **Garmin Switzerland GmbH**,
Schaffhausen (CH)

(72) **Inventors:** **Gregory M. Groener**, Prairie Village,
KS (US); **Mark B. Emge**, Olathe, KS
(US); **Shawn R. Harvill**, Kansas City,
KS (US); **Troy D. Simonton**, Paola, KS
(US)

(73) **Assignee:** **Garmin Switzerland GmbH** (CH)

(**) **Term:** **14 Years**

(21) **Appl. No.:** **29/471,947**

(22) **Filed:** **Nov. 6, 2013**

(51) **LOC (10) Cl.** **10-04**

(57) **CLAIM**

The ornamental design for an electronic device, as shown and described.

DESCRIPTION

FIG. 1 is a front perspective view of an electronic device according to embodiments of the present invention;

FIG. 2 is a rear perspective view of the electronic device;

FIG. 3 is a front view of the electronic device;

FIG. 4 is a top view of the electronic device;

FIG. 5 is a rear view of the electronic device;

FIG. 6 is a bottom view of the electronic device;

FIG. 7 is a left side view of the electronic device; and,

FIG. 8 is a right side view of the electronic device.

Portions of FIGS. 1 through 8 are shown in dashed lines for illustrative purposes only and form no part of the claimed design.
